UNITED STATES PATENT OFFICE

164,166

GOLF PUTTING DEVICE

Stanley M. Griswold, Newton, Mass.

Application May 3, 1950, Serial No. 9,675

Term of patent 14 years

(Cl. D34—5)

To all whom it may concern:

Be it known that I, Stanley M. Griswold, a citizen of the United States, residing at Newton, in the county of Middlesex, Commonwealth of Massachusetts, have invented a new, original, and ornamental Design for Golf Putting Device, of which the following is a specification, reference being had to the accompanying drawing, forming part thereof.

Figure 1 is a top plan view of a golf putting device, showing my new design;

Fig. 2 is a side elevation of the device;

Fig. 3 is a rear elevation of the device; and

Fig. 4 is a longitudinal section on line 4—4 of Fig. 1.

I claim:

The ornamental design for a golf putting device, as shown.

STANLEY M. GRISWOLD.
